UNITED STATES PATENT OFFICE.

ABEL B. W. HODGES, OF GRAND FORKS, CANADA.

FURNACE-CHARGING SYSTEM.

SPECIFICATION forming part of Letters Patent No. 699,525, dated May 6, 1902.

Application filed June 7, 1901. Serial No. 63,581. (No model.)

To all whom it may concern:

Be it known that I, ABEL B. W. HODGES, a citizen of the United States, residing at Grand Forks, in the Province of British Columbia and Dominion of Canada, have invented certain new and useful Improvements in Furnace-Charging Systems, of which the following is a specification.

This invention relates to furnace-feeding, and more especially to the feeding or charging of silver, lead, copper, or copper-matting furnaces, which require to be fed with charges of ore, coke, and flux from the side, top, or end openings through which the charges are introduced.

To this end the invention primarily contemplates a mechanical furnace - charging system comprising instrumentalities so constructed and arranged as to provide positive and reliable means for charging the furnace or furnaces in precisely the manner as may be required by the condition thereof or of the contents therein. In other words, the invention comprehends mechanical means whereby the desired charge may be accurately placed throughout the entire interior area of the furnace or at any point or position therein, as may be required.

A further object of the invention is to utilize in connection with the system dump-cars or carriers which are so constructed relatively to the furnace or furnaces as to admit of being filled or charged in strict conformity with the position to be occupied by the charge in the furnace and comprising means for bodily dropping the charge as an entirety into the furnace.

The invention also has in view the provision of means whereby there is insured a more even distribution of the coke and ore throughout the furnace than is possible by the ordinary hand - feeding. This is especially so when the furnaces are large and running fast, and in the case of a matting-furnace when the top is likely to be hot the feeders in the ordinary hand-feeding operation frequently when unwatched push the coke and charge into the furnace carelessly and promiscuously. This is entirely obviated by the improved mechanical system of feeding or charging contemplated by the present invention, and, besides, a great reduction in labor is ac-

complished, inasmuch as but a few hands are necessary to quickly and positively operate the system.

It is well understood by those familiar with copper-matting and similar furnaces that at times a furnace operates unevenly—as, for instance, the back end may not be properly working down the charge, consequently only requiring a fresh charging at the front end. Also the condition of the furnace at one side may become bad, thus requiring a new charge only on the opposite side until the difficulty is overcome; and, again, it may be desirous and necessary at times to put more or less coke, limestone, or iron-ore in a particular part of the furnace. All of the foregoing contingencies are met by the present invention on account of the same comprising means for depositing the charge in the furnace throughout its entire area or within any portion thereof.

With these and many other objects in view, which will more readily appear as the nature of the invention is better understood, the same consists in the novel construction, combination, and arrangement of parts herein-after more fully described, illustrated, and claimed.

The fundamental feature of the invention involved in the provision of means for mechanically charging the furnace in strict conformity with the position to be occupied therein by the charge is necessarily susceptible to a wide range of modification, and different instrumentalities may be employed for carrying out the system; but a preferred embodiment of the invention is suggested in the drawings, in which—

Figure 1 is a longitudinal sectional view of a furnace-plant equipped with the charging or feeding system contemplated by the present invention. Fig. 2 is a horizontal sectional view on the line 2 2 of Fig. 1, the line of section being immediately above the feed-floor over which is arranged to travel the charge-carrier or dump-car. Fig. 3 is a top plan view of a form of charge-carrier or dump-car which may be advantageously employed in carrying out the system, the view also indicating the approximate dumping area thereof with reference to the cross-sectional area of the furnace. Fig. 4 is a cross-sectional view

of the charge-carrier or dump-car on the line 44 of Fig. 3. Fig. 5 is a detail sectional view, taken longitudinally of one of the charging-apertures, illustrating the preferred manner 5 of handling the ore-buggy when distributing the charge into an empty carrier or car. Fig. 6 is a detail cross-sectional view on the line 66 of Fig. 5.

Like numerals of reference designate corresponding parts in the several figures of the drawings.

The invention may necessarily be carried out in connection with different types of furnaces and modified accordingly to suit the 15 position and nature of the feed-openings for the furnaces, it being understood by those familiar with the art that some forms of furnaces are provided with feed-openings upon opposite sides thereof, others with feed-openings in opposite ends, and also in some furnaces, especially of the silver and lead-smelting type, the same are provided with no feed-doors on the sides or ends, but are in communication with long openings in the feed-floor. These slight variations in the styles of 25 furnaces will not affect the proper carrying out of the invention; but inasmuch as the latter possesses special utility in connection with furnaces of the copper-matting type it 30 has been deemed sufficient for illustrative purposes to show the invention as applied to this class of furnaces, the principle remaining the same in all uses of the invention.

Referring particularly to the drawings, the 35 numeral 1 designates a furnace plant such as usually employed for copper-matting furnaces, and comprising in its organization a building 2, housing therein one or more upright matting-furnaces 3. There are shown 40 in the drawings a pair of these matting-furnaces; but it is obvious that any number may be utilized in connection with the same system of charging. Each of these furnaces is of the general form preferably employed for 45 matting purposes. Furnaces of this type are generally of an oblong rectangular shape in cross-section, as plainly shown in Fig. 2 of the drawings, and in the form illustrated in the drawings project above the plane of 50 the main horizontal feed-floor 4, extending throughout the area within which the furnaces are operated. The portions of the furnaces 3 projecting above the plane of the horizontal main feed-floor 4 are provided in 55 diametrically opposite sides thereof with the feed-openings 5 which are usually covered and uncovered by suitable doors 6, indicated in dotted lines; and said feed-openings are disposed immediately above the plane of the 60 main feed-floor 4 to permit of the passage therethrough of the charge carrier or car 7, which is utilized in the system or apparatus to provide for conveying the charge of ore, coke, &c., to the individual furnaces and 65 bodily depositing the charge therein.

Although any successive arrangement or plurality of furnaces may be observed in car-

rying out the invention, so that the charge carrier or car 7 may be readily run from one to the other in the plant shown in the drawings, the separate furnaces 3 are shown arranged within the same longitudinal plane of the building and have extending transversely through and across the same and through the side feed-openings 5 thereof a track 8, the 75 rails of which track are laid upon the main feed-floor 4 and are adapted to receive thereon the wheels of the charge carrier or car 7.

It is obvious that one or a number of charge carriers or cars may be operated in connection with the system; but, for illustrative purposes, only one of said cars is shown in connection with the pair of matting-furnaces 3, yet in all uses of the invention the charge carrier or car 7 must bear a definite relation 85 in size and shape to the furnace in order to admit of the furnace being charged to suit every condition thereof. The structural details of each charge carrier or car 7 may necessarily vary without affecting the invention, 90 and, in fact, different styles of dump-cars may be utilized as the charge-car, provided the car is of such a construction as to effect the bodily dropping of the charge into the furnace in exactly the position to be occupied by 95 said charge. A preferred type of charge carrier or car is shown in the drawings, and the general characteristics of said car are, first, the construction of the car-body 9 of an approximate W shape in cross-section, thus providing 100 the car-body, upon opposite sides of the vertical longitudinal center thereof, with separate side compartments 10, each of which compartments is provided with outer and inner downwardly-convergent side walls 11 and 12, 105 respectively, the slope of which walls insures a better delivery of the charge into the furnace over which the car may be centered. The separate side compartments 10 of the form of charge carrier or car shown in the 110 drawings extend the full length of the car-body and are provided with bottom discharge-openings 13, adapted to be covered and uncovered by the drop-doors 14, hinged at one edge, as at 15, to the bottom edge of the inner side wall 12 and normally thrown to a closed position when relieved of the weight of the charge through the medium of a weighted closing-arm 16. This weighted closing-arm 115 16 is disposed at such an angle to the drop-door 14 as to provide for automatically closing the same after a charge has been dropped from the compartment with which the doors are associated. The free unhinged edge of each drop-door 14 is adapted to be engaged 120 by the hooked ends 17 of a plurality of pivotal latches 18, which may be conveniently mounted upon a common pivot-rod 19 and are weighted at their upper ends, as at 20, to hold the hooks 17 normally engaged with the 125 free edge of the drop-door. Each series of latches 18 has associated therewith a trip-rod 21, having a handle 22 extending at one side of the car-body, whereby the operator may 130

conveniently release either series of latches. By this construction the separate charges in the separate side compartments 10 of the car-body are independently controllable by the 5 operator.

The car details above described are not essential to the carrying out of the invention; but it is desirable that the car-body be of the same general form as the cross-sectional shape 10 of the furnace, besides having a dumping area approximately equaling the cross-sectional area of the furnace. However, the car-body is somewhat shorter than the major width of the furnace and also narrower 15 than the minor width of said furnace, thus providing means for giving the proper spread to the ore and coke when dropped into the furnace, while at the same time providing for charging the furnace throughout its entire 20 interior area. These characteristics of the charge carrier or car are maintained in all adaptations of the invention in connection with different styles of furnaces.

It is also important in carrying out the invention that the charge carrier or car is properly filled or charged, so that the coke and other material shall be distributed evenly along the entire length thereof. In other words, it is necessary that means be provided for charging or 25 filling the car in strict conformity with the position to be occupied by the charge in the furnace. This may be accomplished through the medium of different instrumentalities; but a practical construction is shown in the drawings, and it consists in providing the main feed-floor 4 with an incline 23, upon which the track 8 is arranged and which slopes downward from the plane of the main portion of the floor into a car-charging pit 25, the roof of 30 which pit is formed by an auxiliary feed-floor section 26, provided therein with a pair of parallel filling or distributing holes 27, constituting charge-apertures, arranged in the same spaced relation as the separate side compartments 10 of the charge-car and of a length equaling the length of such compartments, and providing means for individually filling the separate compartments of the charge-car 35 in conformity with the position to be occupied by the charge in the furnace. The pair of parallel-spaced filling or distributing holes 27 are disposed transversely to the track 8 in the same relation as the furnace or furnaces 3, so that when the charge carrier or car 7 is 40 positioned in the pit 25, directly beneath the floor-section 26, the said holes 27 will be arranged longitudinally of and parallel with the separate side compartments 10 of the car, and also being disposed within the vertical 45 plane of both sides of the latter.

Any suitable means may be resorted to for operating the charge carrier or car back and forth through the furnaces and into and out of the charging-pit 25. A simple and practical way of carrying out this part of the system is shown in the drawings and resides in the employment of an operating-cable 28, ar-

ranged over suitable guides 29 and having separate portions thereof connected to the draft connections 30 at opposite sides of the 70 car and provided upon the car-body frame or truck, which also carries the wheels 31, rolling upon the rails of the track 8. In the construction shown the operating-cable 28 winds and unwinds upon a winding-drum 32, having a reversible motion, and geared with a counter-shaft 33, equipped with fast and loose pulleys 34 and driven from a suitable motor or engine 35. The operating means described provides for imparting a comparatively rapid 80 motion to the discharge-car, whereby in the course of a few minutes the car can make a complete trip in filling a furnace and returning to the charging-pit for refilling.

In further explanation of the manner of 85 charging or filling the carrier or car itself it may be stated that when the carrier or car is in position in the pit 25, directly beneath the filling or distributing holes 27, a helper first brings a weighed amount of coke in a suitable car or buggy and rolls the same to the extreme end of one of the filling or distributing holes 27. He then tips the coke buggy or car until a small portion of the coke falls into the compartment of the charge carrier 90 or car below, and then additional helpers stand in front of the coke-buggy and let only a small amount of coke drop out at a time as the buggy is drawn backward over the entire length of the filling or charging hole, thus 95 providing means for perfectly spreading the coke the entire length of the car. Should it be found desirable or necessary, suitable tracks or guides 36 may be provided upon opposite sides of the holes 27 to facilitate holding the coke and ore buggies to a fixed travel 100 as they are drawn over said holes or apertures. After the spreading of the coke throughout the compartments in the manner described the ore is introduced and spread 105 in the same manner to complete the charge in the charge carrier or car before the latter is moved into the furnace.

The operation just described is plainly illustrated in detail, Figs. 5 and 6 of the drawings. 110 From these figures of the drawings it is seen that when the wheeler brings an amount of coke or ore in his buggy to one end of one of the charging-apertures 27 he dips or tilts the buggy until the nose or point thereof 115 drops upon the floor and transversely bridges or spans the aperture or hole directly below. To secure an effective distribution of the charge it will of course be understood that the charging aperture or hole is narrower 120 than the buggy, so that the latter completely bridges or spans the aperture in the carrier filling or charging operation. It has already been stated that an additional helper or helpers assist in the handling of the ore as it falls 125 from the buggy; but it may be further explained that as soon as the buggy is tipped at one end of the charging-aperture some of the ore or flux necessarily drops out; but as the

wheeler draws the tilted buggy backward over the entire length of the charging-aperture the additional helper with a shovel or other implement holds back and regulates the ore or flux as it falls from the buggy, so as to only let out sufficient material to form an even layer along the entire length of the carrier or car. This is plainly indicated by the illustration of Figs. 5 and 6 of the drawings.

From the foregoing it is obvious that if, for any reason, the charge is only needed in the front end of the furnace the charge carrier or car may be charged at the front end of each compartment and would therefore provide for dropping the charge in the furnace exactly where needed. Also should one side of the furnace get bad the charge could be dropped from one side only of the charge carrier or car, and likewise should it be desirable or necessary to put more or less coke, limestone, or iron ore in any particular part of the furnace the charge-car can be charged accordingly.

From the foregoing it is thought that the operation of the herein-described system will be readily apparent to those familiar with the art without further description; and it will be understood that various changes in the form, proportion, and minor details of construction may be resorted to without departing from the spirit or sacrificing any of the advantages of the invention as claimed.

Having thus described my invention, what I claim as new, and desire to secure by Letters Patent, is—

1. A furnace-charging system comprising in combination with the furnace, a charge-carrier having a charging area the size and shape of the area of the furnace, means for moving the charge-carrier, and charge-distributing means comprehending a charging aperture or apertures the size and shape of the area of the charge-carrier.

2. A furnace-charging system comprising in combination with the furnace, a charge-carrier having a plurality of compartments, the combined dumping area of which approxi-

mately equals the cross-sectional area of the furnace, means for moving the carrier, and charge-distributing means occupying a location above the carrier when in a position to be charged, said charge-distributing means being constructed to effect a distribution of the charge in the carrier in conformity with the position to be occupied thereby in the furnace.

3. A furnace-charging system comprising, in combination with the furnace, a charge-carrier having a charging area the size and shape of the area of the furnace, means for moving the carrier, and means, disposed within the vertical plane of both sides of the carrier when in position to be charged, for effecting a charging of the carrier in conformity with a predetermined position to be occupied by the charge in the furnace.

4. A furnace-charging system comprising in combination with a furnace, a charge-carrier having a charging area the size and shape of the area of the furnace, means for moving the carrier, a charging-pit for the empty carrier, and charge-distributing means arranged above the pit and comprehending a charging aperture or apertures the size and shape of the area of the charge-carrier.

5. In a furnace-charging system, the main feed-floor, the furnace-opening through the said floor, a track arranged on the floor and extending across the furnace, a car-charging pit into which said track extends, an auxiliary feed-floor section constituting the roof of said pit and having elongated filling or distributing holes, a traveling charge-carrier rolling on the track and having several compartments corresponding to said filling or distributing holes, and operating means for moving said carrier over the track.

In testimony whereof I affix my signature in presence of two witnesses.

ABEL B. W. HODGES.
